UNITED STATES PATENT OFFICE

128,662

DESIGN FOR A PLATE OR SIMILAR ARTICLE

Isobel Darrow, Los Angeles, Calif., assignee to Pacific Clay Products, Los Angeles, Calif., a corporation of California

Application May 26, 1941, Serial No. 101,143

Term of patent 14 years

To all whom it may concern:

Be it known that I, Isobel Darrow, a citizen of the United States, residing at Los Angeles, county of Los Angeles, State of California, have invented a new, original, and ornamental Design for a Plate or Similar Article, of which the following is a specification, reference being had to the accompanying drawing, forming part thereof.

Fig. 1 is a top plan view of a plate or similar article, showing my new design.

Fig. 2 is a sectional view taken along the plane
II—II of Fig. 1.

The design as shown in the drawing is in bas-relief. The stippling is for the purpose of showing relief, different portions of the design being differently colored.

I claim:

The ornamental design for a plate or similar article, substantially as shown and described.

ISOBEL DARROW.
